UNITED STATES PATENT OFFICE.

MAURO GUARIGLIA, OF MORGANTOWN, WEST VIRGINIA.

TROLLEY-GUARD.

1,079,408.

Specification of Letters Patent.

Patented Nov. 25, 1913.

Application filed February 3, 1913. Serial No. 746,077.

To all whom it may concern:

Be it known that I, MAURO GUARIGLIA, a non-citizen of the United States, residing at Morgantown, in the county of Monongalia 5 and State of West Virginia, have invented certain new and useful Improvements in Trolley-Guards, of which the following is a specification, reference being had to the accompanying drawings.

This invention relates to new and useful improvements in trolleys or electric railway cars, the object of the invention being to provide an improved means for securing trolley wheels against displacement on the 15 line wire, while the car is in motion.

Another object of the invention is to provide a device of this character which will possess advantages in points of efficiency and durability, is inexpensive of manufacture and at the same time is simple in construction and operation.

With the above and other objects in view, the invention consists in the novel features of construction and the combination and 25 arrangement of parts hereinafter more fully described, pointed out in the claims and shown in the accompanying drawings, in which—

Figure 1 is a side elevation; Fig. 2 is a 30 vertical sectional view; Fig. 3 is a top plan view; Fig. 4 is a detail plan view of the upper end of the arm; Fig. 5 is a front elevation; Fig. 6 is a detail perspective view of one of the retaining arms; Fig. 7 is a detail 35 perspective view of one of the actuating bars; and Fig. 8 is a front elevation of the inner ends of the retaining arms.

Referring more particularly to the drawings, 1 indicates the usual trolley pole having the wire engaging trolley wheel 2 mounted upon the outer end thereof and adapted for normal engagement with the wire 3. Mounted upon the pole 1 adjacent the outer end thereof is a sleeve 4 which is 40 provided with a longitudinal opening 5 and arranged upon each side of the opening 5 are the spaced ears 6. Arranged within the ears are the bolts 7 upon which are mounted the winged nuts 8 whereby the sleeve 4 may 45 be readily applied or removed from the pole.

Projecting outwardly and upwardly from the sleeve 4 is an integrally formed curved

arm 9. The outer end of the arm 9 curves upwardly as shown at 10 and is provided with an enlarged upper end 11 having a flat 55 upper surface as shown at 12, upon which is mounted the plate 13, said plate being secured thereto in any suitable manner. The upper end of the arm 9 is securely braced and held in spaced relation with the outer 60 end of the trolley pole by means of the spaced parallel bracing members 14 integrally formed with the arm and projecting forwardly and secured to the outer end of the trolley pole as shown at 15. 65

Hingedly secured to the front side of the plate 13 is the guard member 16, said guard comprising the spaced side walls 17 which are substantially triangular in shape and integrally connected at one end by means of 70 the transverse member 18. The side walls 17 of the guard member are provided at their ends with outwardly projecting flanges 18' having an opening 19 formed therein. Secured within the opening 19 are the actuating 75 cords 20 which are secured as shown at 21 to the main cord 22. The side walls 17 of the guard member are provided with the transverse alined openings 23 and secured to the outer face of the side walls 17 are the resili- 80 ent angular arms 24, the horizontal portions of which project through the openings 23 and are arranged above the trolley wire to prevent the removal thereof from the guard. The inner ends of the arms 24 are provided 85 with the inwardly beveled portions 25 so that when the wire 3 is engaged thereby, the inner ends of the arms may be readily separated to permit the wire to pass into the guard member. The plate 13 is provided 90 upon its longitudinal edges with the threaded openings 26 which are arranged at diametrically opposite points and are adapted to receive the reduced threaded ends 27 of the tapering bars 28. The bars 28 are dis- 95 posed at an angle with respect to the plate 13 and the upper ends thereof are arranged within the recesses 29 formed within the inner faces of the arms 24 so that the bars 28 are arranged between the arms and the 100 side walls of the guard.

A coil spring 30 is arranged between the plate 13 and the transverse piece 18 which normally retains the guard member in the

position shown in Fig. 2, so that the same will normally retain the trolley wire 3 in engagement with the wheel 2.

In the practical operation of my device, 5 it will be apparent that in Fig. 2, the same is shown in its normal position. In order to release the wire, the cord 22 is pulled downwardly which in turn will move the guard member downwardly toward the 10 plate 23 and upon the downward movement of the guard member, the bars 28 will pass upwardly between the arms 24 and the side walls of the guard member, separating the outer ends of the arms and allowing the 15 wire 3 to pass out of the open end of the guard member. Upon releasing the cord 22, the guard member 16 will pass upwardly, the wire 3 striking the beveled portions 25 and separating the arms 24 suffi- 20 ciently to allow the wire to pass into the open end of the guard member and be disposed beneath the outer ends of the arms 24, thus retaining the wire in engagement with the trolley wheel 2. It will be apparent 25 that upon releasing the cord 22, the spring 30, which has been placed under tension by the downward movement of the guard 16 will return the guard member to its normal position.

30 From the above description taken in connection with the accompanying drawings, it will be readily apparent that I have provided a simple and durable device whereby the trolley wheel will be securely held 35 against accidental displacement on the line wire while the car is in motion. It will also be apparent that the device in itself is extremely simple in construction, efficient and durable in its operation and can 40 be manufactured at a comparatively low cost.

While I have shown and described the preferred form of my invention, it will be obvious that various changes in the details 45 of construction and in the proportion may be resorted to for successfully carrying my invention into practice, without sacrificing any of the novel features or departing from the scope of the appended claims.

50 What I claim is:—

1. The combination with a trolley pole and wheel, of an open ended guard member adapted to receive the trolley wire, angular arms carried by the guard and normally 55 closing the open end thereof to retain the wire into engagement with the wheel, tapering bars adapted to engage and actuate the arms upon the downward movement of the guard to release the wire and means 60 for returning the guard to its normal position.

2. The combination with a trolley pole and wheel, of a sleeve removably mounted upon the pole, a curved arm integrally

formed with the sleeve, an open ended 65 guard member hingedly secured to the upper end of the arm and adapted to receive the trolley wire, means carried by the guard for normally retaining the wire in engagement with the trolley wheel, means 70 actuated by the downward movement of the guard for releasing said wire, and means for returning the guard to its normal position.

3. The combination with a trolley pole 75 and wheel, of a sleeve removably mounted upon the upper end of the pole, a curved arm integrally formed with the sleeve, an open ended guard member hingedly secured to the upper end of said arm and adapted 80 to receive the trolley wire, said guard being provided adjacent its upper end with aligned openings, angular resilient arms secured to the outer faces of the guard and having their horizontal ends disposed 85 through said openings and closing the open end of the guard member to normally retain the wire in engagement with the wheel, means for actuating said arms upon the downward movement of the guard for re- 90 leasing the wire, and means for returning said arms to their normal position.

4. The combination with a trolley pole and wheel, of a removable sleeve mounted adjacent the upper end thereof, a curved 95 arm integrally formed with said sleeve, spaced bracing members formed integral with the arm and having their ends secured to the upper end of the trolley pole, a plate mounted upon the upper end of the curved 100 arm, an open ended guard member hingedly secured to one side of the plate and adapted to normally receive the trolley wire, angular arms carried by the guard member and adapted to close the open end thereof, tapering bars mounted upon the plate and having their upper ends disposed between the arms and the guard whereby, upon downward movement of the guard member, the tapering bars will actuate the arms to 110 release the wire and means for returning the guard member to its normal position.

5. The combination with a trolley pole and wheel, of a sleeve removably mounted adjacent the upper end thereof, a curved arm 115 integrally formed with the sleeve, an enlarged portion formed at the upper end of the arm and provided with a flat surface, a plate mounted upon the upper end of the arm and provided with threaded openings, 120 an open ended guard member hingedly secured to one side of the plate and adapted to normally receive the trolley wire, resilient angular arms carried by the guard and adapted to normally close the open 125 end of the same, tapering bars having their lower ends engaged within the openings in the plate and their upper ends disposed be-

tween the angular arms and the guard member whereby upon the downward movement of the guard member, the arms will be actuated to release the trolley wire, and a coil
5 spring disposed between the upper end of the arm and the guard member to return the guard to its normal position.

In testimony whereof I hereunto affix my signature in the presence of two witnesses.

MAURO GUARIGLIA.
